UNITED STATES PATENT OFFICE.

EDWIN ROSCOE HALL, OF LEGERWOOD, NORTH CAROLINA, ASSIGNOR OF ONE-HALF TO
MRS. ALICE STEELE, OF YADKIN VALLEY, NORTH CAROLINA.

WIRE STRETCHER.

Application filed April 29, 1924. Serial No. 709,802.

To all whom it may concern:

Be it known that EDWIN ROSCOE HALL, a citizen of the United States, residing at Legerwood, in the county of Caldwell and 5 State of North Carolina, have invented certain new and useful Improvements in Wire Stretchers, of which the following is a specification.

This invention relates to improvements 10 in fence wire stretchers and has as its primary object to provide a wire stretcher which may be conveniently employed by one person working alone, to stretch fence wires beside the fence posts and to hold the 15 said wires stretched while being stapled to the posts.

In ordinary fence wire stretchers, difficulty is frequently experienced in holding the stretcher in position to maintain the 20 wire taut while it is being stapled to the post with which the stretcher is engaged, and therefore the present invention has as another important object to provide means whereby the stretcher may be temporarily 25 secured to the posts after the wire has been suitably tensioned and will maintain the position which it at that time occupies, thus permitting of the staples being more readily driven and permitting the user to 30 employ both hands in the operation of securing the wire to the post.

Another object of the invention is to so 35 construct the stretcher that when the fence wire is engaged therewith, the said wire will be firmly and positively gripped so as to provide against any slippage of the wire during the stretching operation, the gripping means being, however, so constructed as to permit of convenient and instantaneous release of the wire after it has been 40 stapled to the post.

Another object of the invention is to so 45 construct the stretcher that it may be employed likewise as a staple puller, so that it is useful not only in stretching fence wires, but also as a means for removing the staples which secure such wires, where the wires are to be replaced as, for example, in repairing the fence.

50 In the accompanying drawing:

Figure 1 is a perspective view of a wire stretcher constructed in accordance with the present invention, the head of the stretcher being illustrated as disposed

against a post to which the stretched wire 55 is to be secured;

Figure 2 is a horizontal sectional view through the stretcher at the head end thereof.

The stretcher comprises a hand lever, 60 which is indicated in general by the numeral 1 and which may be of metal, wood, or any other material found suitable for the purpose, and secured to or forming an integral part with one end of this lever is 65 a post engaging head, indicated in general by the numeral 2. The said head 2 is of approximately arcuate form and is provided with a concave face 3 to which the hand lever 1 is substantially radial, the said 70 lever 1 forming juncture with the back of the head 2 as is clearly shown in the drawing. As fence posts are generally of uniform size, the dimensions of the head 2 and particularly the dimensions and curvature 75 of the engaging face 3 thereof will be determined accordingly so that when the stretcher is applied to a post, the face 3 will embrace one side of the said post.

The head 2 is formed, at one end and at 80 one side of the inner end of the lever 1, with a claw indicated by the numeral 4, and the fingers of this claw, which are indicated by the numeral 5, are separated by a kerf 6 which gradually decreases in width 85 in the direction of the inner end of the claw, so that the confronting faces of the said fingers meet at a relatively acute angle at the inner end of the said kerf. This claw, it will be understood, may be employed in 90 withdrawing staples which have been driven into the posts supporting the fence, and it likewise serves a further purpose to be presently explained.

In its upper side, the hand lever 1 is 95 formed, adjacent its juncture with the head 2, with a recess 7 which opens through the opposite sides of the said lever, and disposed within this recess is the substantially circular head 8 of a gripping eccentric 100 which is indicated by the numeral 9. The head 8 is provided throughout a portion of its periphery with a series of corrugations indicated by the numeral 10, and the said head of the eccentric is freely pivotally 105 mounted upon an eccentrically located pin 11 secured in any suitable manner to the hand lever 1 and upstanding from the bot-

tom wall of the recess 7. A handle 13 extends from the periphery of the head 8 of the gripping eccentric and affords means whereby the eccentric may be moved about its pivot 11. At this point, and particularly by reference to Figure 2 of the drawing, it will be understood that the wire to be stretched and which is illustrated in dot and dash lines in Figure 2 and indicated 10 by the reference letter W, is brought about the post indicated by the reference character P, after the concave face 3 of the head 2 of the stretcher has been disposed against that side of the post adjacent the side 15 against which the wire is initially laid. The wire is then brought through the kerf 6 of the claw 4 and is laid in the recess 7 between one wall 12 thereof and the corrugated peripheral portion 10 of the head 8. 20 By reference to Figure 2 of the drawings it will be observed that the wall 12 of the recess 7 is of arcuate form and is therefore adapted to securely clamp between it and the corrugated periphery of the eccentric 9 25 the wire to be stretched.

As previously stated, the present invention contemplates the provision of means whereby the stretcher may be held or supported in the position which it may assume 30 at the end of the stretching operation, so that both hands of the user will be left free to perform the task of stapling the stretched wire to the fence posts, and this means comprises an arcuate dog, indicated by the numeral 14. The said dog is pivotally mounted at its inner end by a pivot pin 15, between spaced lugs 16, formed at that end of the head 2 opposite the end at which the claw 4 is located, and the curvature of the 40 dog is such as to permit it to substantially embrace one side of the post when the dog is swung inwardly. The dog is provided at its free end with a sharply pointed spur 17 which is presented inwardly and, when the 45 dog has been brought to the dotted line position shown in Figure 2 of the drawings, after the stretching of the wire has been effected, the said spur is driven into the post as shown in full lines in the said figure. 50 In this manner the engagement of the spur of the dog in the post and the tension of the stretched wire cooperate to render the stretcher self-supporting while the wire is being stapled to the post.

If there should be any tendency for the hand lever 1 to swing downwardly, this tendency may be arrested by the means shown in Figure 1 of the drawing and indicated in general by the numeral 18. The 60 said means comprises a length of chain 19 connected to the outer end of the hand lever 1, and a hook 20 connected to the free end

of the chain, the hook 20 being adapted to be engaged with the stretched or taut wire at the most convenient point, for the purpose stated. 65

From the foregoing description of the invention, it will be seen that there is provided a wire stretcher which may be operated by one working alone and which will 70 be self-supporting or sustaining after having been brought to a position where the wire will be stretched and after the spur 17 of the dog 14 has been driven into the post against which the stretcher head is disposed. It will likewise be evident that the engagement of the wire in the restricted inner end of the kerf 6 and likewise the engagement of the wire between the wall 12 of the recess 7 and the corrugated periphery 80 of the head 8 of the gripping eccentric both constitute an efficient means for anchoring the wire to the stretcher while the stretcher is being swung around posts. 75

Having thus described the invention, what is claimed as new is:

1. A wire stretcher comprising a head having a concave side to embrace a post, a hand lever extending from the head, means upon the stretcher for gripping the wire to be stretched, means upon one portion of said head for anchorage to the post to prevent rotative movement of the head about the post, and a claw upon another portion of the head substantially overhanging the gripping means and adapted to receive and guide the wire to said gripping means. 90

2. A wire stretcher comprising a head having a concave side to embrace a post, a hand lever extending from the head, wire gripping means upon the hand lever, a claw upon one portion of the head disposed substantially in alignment with and substantially overhanging the gripping means, said claw being adapted to receive and guide the wire to the gripping means, and means upon another portion of the head for anchorage to the post to prevent rotative movement of the head about the post. 100

3. A wire stretcher comprising a head for engagement with a post, a single hand lever formed integral with and extending laterally from the head, means upon said hand lever for gripping the wire to be stretched, a claw carried by the head substantially 110 overhanging the gripping means and adapted to receive and guide the wire to said gripping means, and a flexible supporting element connected to the outer end of the hand lever and having an element for engagement with the stretched portion of the wire. 115

In testimony whereof I affix my signature.
EDWIN ROSCOE HAEL. [E.S.]
